METHOD OF FORMING BODY BLANKS FOR
RIP STRIP CAN BODIES

Jacob F. Egenolf, Pelham, and Bernard D. Blosier,
Scarsdale, N. Y., assignors to Continental Can
Company, Inc., New York, N. Y., a corporation
of New York

Application May 15, 1945, Serial No. 593,926

3 Claims. (Cl. 164—17)

1

The invention relates to new and useful improvements in a method of making body blanks for can bodies, having score lines setting off a tear strip and a projecting integral tongue to which a key may be attached for removing the tear strip when it is desired to open the can.

An object of the invention is to provide a method of severing a metal sheet so as to provide finished can body blanks having integrally projecting tongue with the least possible waste of material.

A further object of the invention is to provide a method of forming body blanks from a continuous strip by straight line cutting and scroll cutting, followed by slitting and trimming so that finished can body blanks having projecting integral tongues can be produced with a minimum number of operations and the least amount of waste material.

In the drawings:

Figure 1 is a view of a coil strip showing in broken lines the manner of cutting the coil strip to produce sheets therefrom which are properly dimensioned for the forming of body blanks therefrom by the improved method;

Figure 2 is an enlarged view of a sheet formed from the coil strip by the straight line cutting of the same indicated in Figure 1;

Figure 3 is an enlarged view of one of the sections cut from the sheet in Figure 2 from which a single body blank is to be trimmed;

Figure 4 shows the body blank at the scroll edge trimmed so as to provide the integrally projecting tongue and the parts which are to be folded to form the hooks for the joining of the ends into a side seam for the can body;

Figure 5 is a view showing the hooks formed at the integral tongue end of the body blank;

Figure 6 is a detail upper edge view of the portion of the body blank shown in Figure 5.

Referring to Figure 2, there is shown a sheet of metal wherein the sides and ends have been squared preparatory to the cutting of the sheet into sections for forming body blanks. This sheet as shown in Figure 2, may be furnished by the mill or the sheet may be produced from a coil strip. As illustrated in the drawings, the sheet is formed from a coil strip indicated at 1, by cutting the strip along the lines 2—2 and 3—3. After the sheet which is designated at 4 in the drawings has been cut from the coil sheet or received from the mill, it is scroll cut along the lines 5—5. This sheet is dimensioned so that two can body blanks may be formed from each section produced by the scroll line cut 5—5. The sheet, of course, could be of a greater width 55

2

so that three or more can body blanks can be cut from each section of the sheet formed by the scroll cutting.

The length of the sheet is such that when it is scroll cut along the line 5—5, each section will be of proper dimensions so that body blanks with projecting integral tongues can be formed therefrom. In the scroll cutting of the sheet 4 the section 4a will be provided with a scroll projection 6 and a recess 7. When the sheet is of a width for forming two body blanks from each section, there will be two scroll projections 6—6 and two recesses 7—7.

This cutting of the sheet to form a section 4a with a scroll projection and recess also produces a section 4b wherein there are similar projections and similar recesses. The scroll projection 6 on the section 4a produces the recess in the section 4b and likewise, the scroll projection on the section 4b forms the recess 7 on the section 4a. After having scroll-cut the sheet 4 so as to provide the two sections 4a and 4b, each section is then slit along the line 8—8 so that from each section there is produced two metal parts of proper dimensions for forming a body blank therefrom. One of these parts is indicated at 9, in Figure 3, and may be termed a preliminary blank from which the finished can body blank is formed.

30 This metal part 9 has a width equal to the height of the can body. The bottom end of the can body is indicated by the line 10 and the top end of the can body is indicated by the line 11.

The scroll end of this part 9 is next cut along 35 the dot and dash line 12—12 and also along the dot and dash lines 13—13 which form the tearing tongue, indicated at 14. The trimmed end is shown in Figure 4. This trimming operation forms hooks for the side seam, the hook section

40 above the tongue being indicated at 15, the hook section between the tongue and the recess 7 being indicated at 16, and the hook section between the recess 7 and the lower end of the can being indicated at 17. These hook sections are 45 formed by bending the blank along the broken line 18'.

In Figure 5 the hooks have been bent back upon the body in the usual way so they are ready to be interlocked with the usual hook formed at 50 the opposite end of the can body. It is understood that the body blank is intended for what is well known as a lock and lap side seam. The lap portions, however, have not been indicated in the drawings in order to avoid confusion.

Before the trimming of the body blank, or at

the time of trimming or subsequently thereto, the body blank is scored along the lines 18 and 19, thus setting off a tear strip which is in alignment with the tearing tongue 14.

Referring again to Figure 2, the tongues formed on each body blank at the final trimming operation are indicated in broken lines in this figure. Likewise the trimming lines for the forming of the hooks and also the score lines are shown in this figure. It will be noted that this sheet 4, whether it is furnished by the mill or made from a coil strip, is severed by a scroll cut so as to provide two sections, each section having one edge which is straight and the other scrolled, with the scrolled edge having alternately arranged projections and notches of a similar size and shape in spaced relation and equidistant from the side edges of the body blanks to be formed from said section.

Said section is also dimensioned so that the width thereof is equal to the height of a body blank or a multiple thereof, and the overall length of the section at the scroll projection is equal to the length of a finished can body blank plus the length of a tongue. The length of the strip at the scroll recess is equal to the length of a finished body blank less the length of one body hook. The length of the tongue wherever referred to is that portion of the tongue extending beyond the edge of the body blank. It will also be noted that the inner edge of the recess 7 is coincident to the bend line of the can body hooks.

It is from this section of metal formed by this scroll cutting and slitting of the sheet that the body blanks are formed. The number of operations for forming the body blanks from the sheet has been reduced to a minimum. The first operation is a scroll cut, the next operation is slitting and transverse straight line cutting where a coil strip is being operated upon and the third operation is die trimming, notching, and scoring, and what might be called a fourth operation is the bending of the hooks which may be performed in the same operation as the trimming.

In the usual commercial method of forming can body blanks, each body blank is separately formed and must be cut from a sheet of metal, which equals the length of the finished body blank plus the length of the tongue minus the width of a hook. Applicant, by the improved method described above reduces the amount of waste to a minimum as the length of the sheet for forming two can body blanks end to end therefrom is less than the length of a tongue and one body hook. It has been proposed to cut two body blanks from a sheet end to end with the tongues of the two blanks staggered. This would be a considerable saving of material over the commercial method referred to above. By this proposed method the waste material is of a width at least equal to the length of a tongue less the width of one hook as the tongue is cut solely from this waste material. By the method described above and set forth in the claims there is a marked additional saving of material. The waste in material between the ends of the blanks is equal to the length of the tongue less the width of two hooks and, therefore, by this method over the proposed method, there is a saving of at least the width of one hook. This may seem like a small saving, but cans of this tearing strip type are made by the millions, and when the saving on one blank is multiplied by the great number of body blanks that are formed with tearing strips

and projecting tongue the saving is very material.

While the method has been described as consisting in scroll cutting a sheet having straight parallel ends, the method may be equally applied to the scroll cutting of the coil strip along the lines 20-20 and 21-21, thus forming a sheet, each end of which is scroll cut. In such a carrying out of the method, the sheet thus formed would be slit along the line 3-3 centrally thereof, thus forming sections of the sheet which, when slit, would form the parts 9 from which the body blanks are produced, with the same saving of metal.

It is obvious that minor changes in the steps of the method may be made without departing from the spirit of the invention as set forth in the appended claims.

We claim:

1. The method of making a sheet metal can body blank for a can having a tearing strip and an integrally projecting tongue, comprising forming a metal section by scroll cutting one edge thereof in a single cutting operation and straight cutting the other edge in a single cutting operation so that the metal section has two generally parallel edges at right angles to the side edges thereof, said scroll edge having alternately arranged projections and recesses of similar size and shape in spaced relation and equidistant from the side edges of the body blanks to be formed from said metal section, said metal section being dimensioned so that the width thereof is equal to the height of a body blank or a multiple thereof and the overall length of the metal section at the scroll projection is equal to the length of a finished can body blank plus the length of a tongue, and the length of the strip at the scroll recess is equal to the length of one finished can body blank less the length of one body hook, the inner edge of the recess formed by the scroll cut being coincident to the bend line of the can body hooks, slitting said metal section into preliminary body blanks, trimming the scroll edge of the preliminary blank so as to provide a finished can body blank and provide a projecting tongue from the scroll projection of the preliminary blank.

2. The method of making a sheet metal can body blank for a can having a tearing strip and an integrally projecting tongue comprising cutting a coil strip so as to provide a sheet with straight parallel ends, subsequently scroll cutting said sheet midway between its ends in a single cutting operation so as to provide two metal sections of the same size, each having a straight edge and a scroll edge, said scroll edge having alternately arranged projections and recesses of similar size and shape in spaced relation and equidistant from the side edges of the body blanks to be formed from said metal section, said metal section being dimensioned so that the overall length of the metal section at the scroll projection is equal to the length of a finished can body blank plus the length of a tongue and the length of the metal section at the scroll recess is equal to the length of one finished can body blank less the length of one body hook, the inner edge of the recess formed by the scroll cut being coincident to the bend line of the can body hooks, slitting said metal section into preliminary body blanks, forming the scroll edge of the preliminary blank so as to provide a finished can body blank and also provide a projecting tongue from the scroll projection of the preliminary blank.

3. The method of making a sheet metal can body blank for a can having a tearing strip and

an integrally projecting tongue comprising scroll cutting a coil strip so as to provide a sheet with generally parallel ends, subsequently cutting said sheet on a straight line midway between its ends so as to provide two metal sections of the same size, each section having a straight edge and a scroll edge, said scroll edge having alternately arranged projections and recesses of similar size and shape in spaced relation and equidistant from the side edges of the body blanks to be formed from said metal section, said metal section being dimensioned so that the overall length of the metal section at the scroll projection is equal to the length of a finished can body blank plus the length of a tongue and the length of the metal section at the scroll recess is equal to the length of one finished can body blank less the length of one body hook, the inner edge of the recess formed by the scroll cut being coincident to the bend line of the can body hooks, slitting said metal section

into preliminary body blanks, forming the scroll edge of the preliminary blank so as to provide a finished can body blank and also provide a projecting tongue from the scroll projection of the preliminary blank.
